No. 683,542.

C. C. WORTHINGTON.

Patented Oct. 1, 1901.

PUMP.

(Application filed Apr. 4, 1900.)

· (No Model.)

THE NORRIS PETERS CO., PHOTO-LITHO., WASHINGTON, D. C.

UNITED STATES PATENT OFFICE.

CHARLES C. WORTHINGTON, OF DUNNFIELD, NEW JERSEY.

PUMP.

SPECIFICATION forming part of Letters Patent No. 683,542, dated October 1, 1901.

Application filed April 4, 1900. Serial No. 11,517. (No model.)

To all whom it may concern:

Be it known that I, CHARLES C. WORTHINGTON, a citizen of the United States, residing at Dunnfield, county of Warren, and State of New Jersey, have invented certain new and useful Improvements in Pumps, fully described and represented in the following specification and the accompanying drawings, forming a part of the same.

10 The object of the present invention is to provide an improved construction of pump end for steam or other power pumps which shall be simple, cheap, and durable in construction, attractive in appearance, compact and of light weight, and with short and direct passages for the fluid to be pumped. I aim particularly at the production of such a duplex pump, and certain features of the invention are limited to duplex-pump constructions; but the invention, broadly considered, includes also constructions in single pumps.

15 For a full understanding of the invention a detailed description of a construction embodying all the features of the invention in their preferred form as applied to a duplex pump will now be given in connection with the accompanying drawings, forming a part of this specification, and the features forming the invention then particularly pointed out

20 in the claims.

In the drawings, which show the pump end of a duplex or two-cylinder pump, which may be of any general construction, such as that of well-known direct-acting or crank pumps, Figure 1 is a side elevation of the pump. Fig. 2 is an end view looking to the left in Fig. 1, or toward the power end of the pump. Fig. 3 is a vertical cross-section on the line 3 of Figs. 1 and 4. Fig. 4 is a vertical longitudinal section on the line 4 of Figs. 2 and 3. Fig. 5 is a horizontal section on the line 5 of Figs. 1, 2, and 3. Fig. 6 is a sectional side elevation on the line 6 of Fig. 3.

Referring to said drawings, A A' are the water-cylinders on opposite sides of the pump, and a a' the corresponding pistons or plungers, having piston or plunger rods b b'.

B B' are the pulsation-chambers for the respective cylinders A A', extending longitudinally of and in line with the cylinders and divided by partitions 13 to form chambers for

the opposite ends of the double-acting pump shown.

C is the suction-chamber common to the two sides of the pump and extending longitudinally of the cylinders between the pulsation-chambers B B', and D is the force-chamber on the sides of the pump outside of the two pulsation-chambers B B' and having a portion D' extending over the top of the suction and pulsation chambers centrally of the pump and transversely to the cylinders. The suction-chamber is shown as opening at both ends of the pump, which is preferable, so that the suction-main connection may be made at either end, as desired, and E is the suction-main, shown as connected at the rear or outer end of the pump, the suction-port at the other end of the suction-chamber being closed by cover 10. The force-main F connects with the top portion D' of the force-chamber centrally at the top of the pump. The suction and force chambers are separated from the pulsation-chambers by valve-plates 11, arranged edgewise to the cylinders—that is, vertically in the pump shown—and extending longitudinally of the cylinders. In these valve-plates are the suction-valves c and force-valves d, which are shown as the common voluntary valves, each of these sets of valves being shown as consisting of two horizontal rows.

The top of the suction and pulsation chambers is closed by a web 12, extending over the valve-plates 11, and convenient access to the force-valves on opposite sides of the pump is provided by side hand-holes having covers 14 and to the suction-valves by top hand-holes on opposite sides of the upper part of the force-chamber D, having covers 15.

It will be seen from the drawings that the cylinders, valve-plates, and all the pump-chambers, including the force-chamber, may be made in a single casting of simple form, and this is preferable, my improved construction permitting the force-chamber, as well as the other chambers, to be formed integral with the cylinders instead of bolting on a separate force-chamber. It will be understood, however, that the invention is not limited to such a single-casting construction, although this forms a specific feature of the

invention. It is clear from the drawings that a very compact, strong, and light duplex-pump construction is secured by my invention, while the construction is very efficient 5 and desirable on account of the directness of the various passages, the valves are readily accessible, and the cost of the construction as compared with other pumps of the same capacity is reduced, not only by the large 10 reduction in the weight and amount of material, but also in the labor required in manufacture.

I preferably use a construction in which the valve-plates and valves are arranged so 15 as to economize space and secure a more compact construction by utilizing the variation in flow of the fluid in different parts of the pulsation and suction chambers, the flow of fluid in the pulsation-chamber being less at 20 the top than at the bottom, and vice versa in the suction-chamber. This result is secured by making the suction-chamber increase in width from the cylinder and the pulsation-chamber increase in width toward the cylinder. 25 As shown in the drawings, the valve-plates 11 are stepped at 1 between the two horizontal rows of valves, so that the suction-chamber is narrow at the bottom and wide at the top and the pulsation-chambers are wide 30 at the bottom and narrow at the top, thus saving largely in the width of the pump required for a given capacity.

From the illustration in the drawings and the above description of the invention as applied to a duplex pump the construction of 35 a single pump involving the broad invention will be clear, as such a single pump may consist simply of one-half of the duplex pump shown, the pump being divided longitudinally between the cylinders, and the force-main may connect with the top of the pump, as shown, or with the side of the force-chamber, and the suction-main may connect either at the end of the pump, as in the construction shown, or at the side of the suction-chamber, as desired. In either a single or duplex 40 pump the connection of the force-main at the top and the suction-main at the end of the pump is desirable, as it reduces the floor-space 45 occupied by the pump and its connections.

While the invention has been illustrated and described as applied to double-acting pumps, it will be understood that, broadly considered, the invention is applicable also 55 to single-acting pumps, such construction being obvious from the drawings. It will be understood also that many modifications in the construction shown may be made by those skilled in the art without departing from the 60 invention and that I am not to be limited to the exact form or arrangement of parts shown in the drawings.

What I claim is—

1. The combination with a pump-cylinder, 65 of suction and force valve plates arranged edgewise to the pump-cylinder and extending longitudinally of the cylinder, a pulsation-

chamber between said plates, and suction and force chambers on opposite sides of the pulsation-chamber, substantially as described. 70

2. The combination with a pump-cylinder, of suction and force valve plates arranged edgewise to the pump-cylinder and extending longitudinally of the cylinder, a pulsation-chamber between said plates, and suction and force chambers on opposite sides of the pulsation-chamber, said valve-plates being shaped 75 to form a pulsation-chamber increasing in width toward the cylinder and a suction-chamber increasing in width from the cylinder, substantially as described.

3. The combination with a pump-cylinder, and a pulsation-chamber arranged in line with and extending longitudinally of the cylinder and opening directly from the cylinder, 85 of suction and force chambers extending longitudinally of the cylinder on opposite sides of the pulsation-chamber, and suction and force valve plates extending longitudinally of the cylinder between the pulsation-chamber 90 and the suction and force chambers, substantially as described.

4. In a double-acting pump, the combination with the pump-cylinder, of suction and force valve plates arranged edgewise to the pump 95 cylinder and extending longitudinally of the cylinder, pulsation-chambers for the opposite ends of the pump between said plates, and suction and force chambers extending along both pulsation-chambers on 100 opposite sides of the pulsation-chambers, substantially as described.

5. In a double-acting pump, the combination with the pump-cylinder, of pulsation-chambers for the opposite ends of the pump 105 arranged in line with and extending longitudinally of the cylinder and opening directly from the cylinder, suction and force chambers extending longitudinally of the cylinder and along both pulsation-chambers on opposite sides of the pulsation-chambers, and suction and force valve plates extending longitudinally of the cylinder between the pulsation-chambers and the suction and force 110 chambers, substantially as described. 115

6. In a duplex pump, the combination with the pump-cylinders, of suction and force valve plates arranged edgewise to the cylinders and extending longitudinally of the cylinders, a central suction-chamber, pulsation-chambers for the two sides of the pump on 120 opposite sides of the suction-chamber, and a force-chamber extending outside said pulsation-chambers on opposite sides of the pump, substantially as described. 125

7. In a duplex pump, the combination with the pump-cylinders, of suction and force valve plates arranged edgewise to the cylinders and extending longitudinally of the cylinders, a central suction-chamber, pulsation-chambers for the two sides of the pump on 130 opposite sides of the suction-chamber, and a force-chamber extending outside said pulsation-chambers on opposite sides of the pump,

said valve-plates being shaped to form pulsation-chambers increasing in width toward the cylinders and a suction-chamber increasing in width from the cylinders, substantially as described.

8. In a duplex pump, the combination of the pump-cylinders, pulsation-chambers for the opposite sides of the pump extending longitudinally of the respective cylinders, a suction-chamber between said pulsation-chambers, a force-chamber extending outside the pulsation-chambers on opposite sides of the pump, and suction and force valve plates extending longitudinally of the cylinders between the pulsation-chambers and the suction and force chambers, substantially as described.

9. In a duplex pump, the combination of the pump-cylinders, pulsation-chambers for the opposite sides of the pump extending longitudinally of the respective cylinders, a suction-chamber between said pulsation-chambers, a force-chamber extending outside the pulsation-chambers on opposite sides of the pump and over the top of the pulsation and suction chambers, and suction and force valve plates extending longitudinally of the cylinders between the pulsation-chambers and the suction and force chambers, substantially as described.

10. In a duplex pump, the combination of the pump-cylinders, pulsation-chambers for the opposite sides of the pump extending longitudinally of the respective cylinders, a suction-chamber between said pulsation-chambers, a force-chamber extending outside the pulsation-chambers on opposite sides of the pump and longitudinally of the cylinders, and valve-plates extending longitudinally of the cylinders between said chambers, all formed integral, substantially as described.

11. In a duplex pump, the combination of the pump-cylinders, pulsation-chambers for the opposite sides of the pump arranged in line with and longitudinally of the respective cylinders, a suction-chamber between said pulsation-chambers, a force-chamber extending outside the pulsation-chambers on oppo-

site sides of the pump and over the top of the pulsation and suction chambers, and valve-plates extending longitudinally of the cylinders between said chambers, all formed integral, substantially as described.

12. The combination with a pump-cylinder, of a suction-chamber and pulsation-chamber arranged side by side with the suction-chamber increasing in width from the pump-cylinder and the pulsation-chamber increasing in width toward the cylinder, substantially as described.

13. A pump having stepped valve-plate 11 with suction-valves on opposite sides of the step, and suction and pulsation chambers on opposite sides of the plate, substantially as described.

14. A pump having stepped suction and force valve plates 11, each with valves on opposite sides of the step, and suction and force chambers on opposite sides of the pulsation-chamber, substantially as described.

15. A duplex pump having the cylinders A, A', central suction-chamber C, pulsation-chambers B, B' on opposite sides of the suction-chamber, force-chamber D outside the pulsation-chambers, all said chambers extending longitudinally of the cylinders, and top force-chamber extension D' extending across the pump for connection with the force-main, substantially as described.

16. A duplex pump having its force-chamber extending over the top and at opposite sides of the pump and a central suction-chamber, and having the top portion of the force-chamber arranged centrally of the pump and of such width as to permit access to the suction-valves at the top of the pump independently of the force-chamber, substantially as described.

In testimony whereof I have hereunto set my hand in the presence of two subscribing witnesses.
